JONATHAN LUCAS, OF SAVANNAH, GEORGIA, ASSIGNOR TO LUCAS-LAMBORN LOOM CORP., OF NEW YORK, N. Y., A CORPORATION OF NEW YORK.

BOBBIN FOR LOOMS.

Application filed October 31, 1925. Serial No. 65,934.

My invention relates to bobbins for looms and has for its object to provide the bobbin with a simple and efficient device which is maintained in an inoperative position by the supply of yarn on the bobbin and which is constructed and arranged to automatically assume an operative position, when said supply of yarn is exhausted, to bring about a stoppage of the loom mechanism or 10 a substitution of bobbins. The invention contemplates particularly a novel construction in which the aforesaid device is automatically adjusted to its inoperative position when the bobbin is placed upon the 15 spindle of a winding machine for rewinding a supply of yarn on said bobbin. The invention will be fully described herein-after and the features of novelty will be pointed out in the claims.

20 In the accompanying drawings, which illustrate an example of the invention without defining its limits, Fig. 1 is an exterior view of the bobbin, partly in section, with the invention incorporated therein; Fig. 2 is an 25 end view thereof; Fig. 3 is a sectional view on the line 3—3 of Fig. 1; Fig. 4 is a view similar to Fig. 1 showing the bobbin in section with a supply of yarn thereon; Fig. 5 is a cross-section on the line 5—5 of Fig. 4; 30 Fig. 6 is a view of the shuttle with the novel bobbin in place therein and Fig. 7 is a cross-section on the line 7—7 of Fig. 6.

The bobbin itself may be of any well known and conventional type and in the illustrated example comprises a base 10 tapering toward and comprising an axial continuation of a stem 11, the outer surface of said base 10 being preferably stepped in the customary manner. The stem 11 is provided 40 with the conventional bore 12 which extends lengthwise of the stem, and in the illustrated arrangement communicates with a chamber 13 located internally of the bobbin of the base 10 thereof; the bobbin is further constructed in such a manner as to enable it to be detachably mounted in the customary shuttle, and for this purpose may be provided with a sleeve 14 connected with the free end of the base 10 and forming a continuation thereof as shown in the drawings. The aforesaid chamber 13 is preferably of 50 inwardly tapering form and at its apex end

is of somewhat larger diameter than the inner diameter of the bore 12 at this point so as to form an internal shoulder 15 as 55 shown in Figs. 1 and 3; a slot 16 is formed in the base 10 so as to communicate with said chamber 13 for a purpose to be more fully described hereinafter, a second slot 17 being formed in line therewith at the free 60 end of the base and being located partly in the base 10 and partly in the sleeve 14. In some cases this second slot 17 may be omitted, the presence or absence of this slot 17 depending upon the physical characteristics of the device which constitutes the present invention.

In the illustrated example the device, whereby the stopping of the loom mechanism or a substitution of a filled bobbin for an empty one, automatically takes place when the supply of yarn upon the given bobbin has been exhausted, comprises a tripping member 18 located in registry with the slot 16 and adapted to project therethrough in an operative position when the supply of yarn upon the bobbin is exhausted. This tripping member is yieldingly mounted in the chamber 13, and as shown may comprise an integral portion of the member 19 of an approximately V-shaped spring, the other leg 20 of which lies in surface engagement with the inner surface of the chamber 13; at its free end the leg 20 is provided with a projection 21 seated in an aperture 10a 85 of the base 10. The aforesaid V-shaped spring is coiled upon itself to form an eyelet 22 located in axial registry with the bore 12 and in engagement with the aforesaid internal shoulder 15. To facilitate the manual adjustment of the tripping member 18 to its inoperative position, if for any reason this becomes necessary or desirable, the free end of the member 19 may be bent to form a finger piece 23 located in registry with the slot 17 and projecting outwardly there- 90 through when the tripping member is in its operative position as shown in Fig. 1. The device comprises further a cone-shaped controlling member 24 having its one end formed with a suspending member 25 to suspend said controlling member 24 at its one end from the member 19 of the V-shaped spring as shown in Fig. 1. To facilitate the

combination of the parts the controlling member 24 may be slotted as indicated at 26 in Fig. 3.

When the bobbin is empty, that is when 5 the supply of yarn therein is exhausted, the parts occupy the position shown in Fig. 1, in which the V-shaped spring is removably fixed in the chamber 13 with the members 19 and 20 thereof in surface engagement with 10 the wall of the chamber 13 and with the eyelet 22 resting against the shoulder 15. Under these conditions the tripping member 18 and the finger piece 23 project outwardly through the slots 16 and 17 respectively and 15 the projection 21 is seated in the aperture 10^a; in this position of the parts the controlling member 24 is suspended from the member 19 at an inclination toward the free end of the base 10, the arrangement being 20 such that the controlling member 24 flares outwardly towards the same as shown in Figs. 1, 2 and 3.

For the purpose of winding a supply of 25 yarn upon the bobbin the latter, generally speaking, is mounted upon the spindle 27 of a winding machine in the customary manner, said spindle extending into the bore 12 in frictional engagement with the surface thereof. As the bobbin is placed in position 30 upon the spindle 27, the latter will move lengthwise of the interior surface of said controlling member 24. Because of the flaring form of the latter and due to the inclined position occupied by the member 24 35 when the bobbin is empty, this movement of the spindle 27 relatively to the member 24 will exert a camming action thereon which tends to bring the smaller apex end of said member 24 into axial registry with the bore 12; in other words the aforesaid apex end 40 of the member 24 is shifted inwardly from the position shown in Fig. 1, and because of its positive connection with the member 19 will correspondingly shift the latter and 45 thereby withdraw the tripping member 18 to its inoperative position as shown in Figs. 4 and 5. In such inoperative position, the tripping member lies entirely within the outer surface of the base 10; at the same 50 time the finger piece 23 is correspondingly moved to the position shown in Fig. 4. As the combination of the parts is continued, the spindle will finally pass through the eyelet 22 and become seated in the bore 12 in 55 the manner indicated in Fig. 4, in which position the surface of the spindle is frictionally engaged by the eyelet 22; this frictional engagement between the spindle and the eyelet assists in maintaining the bobbin 60 against rotation relatively to the spindle 27, it being understood that any other means conventionally used for preventing such rotation may be also included in the arrangement if desired. The winding of the yarn 65 upon the bobbin then proceeds in the cus-

tomary manner until a complete supply 28 is again carried thereby, said winding, as shown in Fig. 4, extending over the base 10 and thus covering the slot 16. When the bobbin is again fully wound, that portion of 70 the yarn which is wound upon said base 10 serves to prevent the tripping member 18 from shifting outwardly through the slot 16 or in other words maintains it in an inoperative position against the inherent tension 75 of the V-shaped spring. After having been fully wound, the bobbin is withdrawn from the spindle 27 and the tripping device is maintained in its inoperative position by the yarn 28 as set forth above. 80

When combined with the shuttle 30 the bobbin is mounted in the chamber 31 thereof in any customary manner as indicated in Fig. 6. With the arrangement set forth, the tripping member 18 will remain in its inoperative position as long as a sufficient amount of yarn remains upon said bobbin. When the supply of yarn reaches its last 90 few convolutions upon the base 10, the resistance will be insufficient to maintain the 95 tripping member 18 against the resiliency of the V-shaped spring. As soon as this condition is reached, the member 18 will be automatically projected through the recess 16 to its operative tripping position beyond the surface of the bobbin base 10 as shown in Figs. 1 and 2. The member 18 thus lies in the path of a member 29 which accordingly comes into contact therewith and thereby either causes a stoppage of the loom 100 mechanism or brings about an operation of the magazine mechanism whereby the empty bobbin is removed from the shuttle and a new one is substituted therefor. 105

It will be noted that no manual or other extraneous manipulation of the tripping device is required to bring the tripping member 18 to its inoperative position when it is desired to rewind the bobbin with a new supply of yarn. The setting of the tripping 110 member 18 to its inoperative position is automatically accomplished by the mere act of placing the bobbin upon the spindle of the winding machine and is brought about as hereinbefore stated by the cooperation of 115 the spindle 27 with the controlling member 24. It will be seen from the drawings that the V-shaped spring and its related elements may readily be removed from the chamber 13 by shifting the members 18 and 23 inwardly out of the slots 16 and 17 respectively and by withdrawing the projection 21 from the aperture 10^a. Heretofore in devices of the character herein described, the setting of the tripping device to its inoperative position, during the initial steps of winding a supply of yarn upon the bobbin, has been brought about manually or through the medium of more or less complicated arrangements. With the present invention the ne- 120 125 130

cessity for manual operation is entirely avoided and complicated devices to attain the desired results are done away with.

Various changes in the specific form shown and described may be made within the scope of the claims without departing from the spirit of my invention.

I claim:—

1. The combination of a bobbin of the kind described, a tripping device carried by said bobbin and held in an inoperative position thereon by the yarn upon said bobbin, said device automatically assuming an operative tripping position when the supply of yarn on said bobbin is exhausted and independent means carried by said bobbin and connected with said tripping device whereby the latter is automatically adjusted to its inoperative position when said bobbin is placed upon the spindle of a winding machine for receiving a supply of yarn.

2. The combination of a bobbin of the kind described, a tripping device carried by said bobbin and held in an inoperative position thereon by the yarn upon said bobbin, said device automatically assuming an operative tripping position when the supply of yarn on said bobbin is exhausted and independent means carried by said bobbin and connected with said tripping device, said means co-operating with the spindle of a winding machine to automatically adjust said tripping device to its inoperative position when said bobbin is placed upon said spindle for receiving a supply of yarn.

3. The combination of a bobbin of the kind described, a tripping device carried by said bobbin and held in an inner inoperative position thereon by the yarn upon said bobbin, said device automatically shifting outwardly to an operative tripping position when the supply of yarn upon said bobbin is exhausted and an independent device carried by said bobbin and connected with said tripping device whereby the latter is automatically drawn inwardly to its inoperative position and held therein when said bobbin is mounted upon a winding machine for receiving a supply of yarn.

4. The combination of a bobbin having a base and a stem, said base being provided with a surface slot and an interior chamber in communication therewith and said stem having an axial bore forming a continuation of said chamber for the reception of the spindle of a winding machine, a tripping device mounted in said chamber and including a tripping member normally held in an inoperative position, in registry with said slot, by the yarn upon said bobbin and automatically shifting outwardly through said slot to an operative tripping position when the supply of yarn upon said bobbin is exhausted and an independent setting member

loosely connected with said tripping device and adapted, for engagement with said spindle to automatically adjust the tripping member to its inoperative position when said bobbin is placed upon said spindle for receiving a supply of yarn.

5. The combination of a bobbin having a base and a stem, said base being provided with a surface slot and an interior chamber in communication therewith and said stem having an axial bore forming a continuation of said chamber for the reception of the spindle of a winding machine, an approximately V-shaped spring coiled upon itself at its apex end to form an eyelet located within said chamber in registry with said axial bore and having its legs located within said chamber, a tripping member on one of said legs in registry with said slot normally held in an inoperative position by the yarn upon said bobbin and arranged to automatically snap outwardly through said slot, to an operative tripping position, when the supply of yarn upon said bobbin is exhausted and a hollow, tapering, setting member having its apex end suspended from the tripping member leg of said spring and arranged to co-operate with said spindle to shift said leg inwardly and automatically set said tripping member in its inoperative position when said bobbin is placed upon said spindle for receiving a supply of yarn.

6. The combination of a bobbin of the kind described provided with a slot in its surface and having an open chamber at its one end communicating with said slot, a tripping member normally held in said slot in an inoperative position by the yarn upon said bobbin, a spring fitted in said chamber and connected with said tripping member whereby the latter is projected out of said slot and the tripping member is coincidentally projected out of said recess to an operative tripping position when the supply of yarn on said bobbin is exhausted and a cone shaped member located within said chamber and connected with said spring, said cone shaped member cooperating with the spindle of a winding machine to automatically reset said tripping member to an inoperative position.

7. The combination of a bobbin of the kind described provided with a slot in its surface and having an open chamber at its one end communicating with said slot, a tripping member normally held in said slot in an inoperative position by the yarn upon said bobbin, a spring fitted in said chamber and connected with said tripping member whereby the latter is projected out of said slot to an operative tripping position when the supply of yarn on said bobbin is exhausted and a loop on said spring in axial registry with said chamber for frictionally

surrounding and gripping the spindle of a winding machine to hold and centre the bobbin thereon.

8. The combination of a bobbin of the kind described provided with a slot in its surface and having an open chamber at its one end communicating with said slot, a tripping member normally held in said slot in an inoperative position by the yarn upon said bobbin, a spring fitted in said chamber and connected with said tripping member whereby the latter is projected out of said slot to an operative tripping position when the supply of yarn on said bobbin is exhausted, a cone shaped member located within said chamber and connected with said spring, said cone shaped member cooperating with the spindle of a winding machine to automatically re-set said tripping member to an inoperative position and a loop on said spring in axial

registry with said chamber for frictionally engaging said spindle to hold and centre the bobbin thereon.

9. The combination of a bobbin of the kind described, a tripping device carried by said bobbin and held in an inoperative position thereon by the yarn upon said bobbin, said device automatically assuming an operative position when the supply of yarn on said bobbin is exhausted, and an independent cone shaped member carried by said bobbin and connected with said tripping device, said cone shaped member cooperating with the spindle of a winding machine to automatically re-set the tripping device to an inoperative position.

In testimony whereof I have hereunto set my hand.

JONATHAN LUCAS.
